UNITED STATES PATENT OFFICE.

LEVI D. VAN VALKENBURGH, OF HOLYOKE, MASSACHUSETTS.

SPINDLE AND BEARING.

SPECIFICATION forming part of Letters Patent No. 324,900, dated August 25, 1885.

Application filed September 30, 1884. (No model.)

To all whom it may concern:

Be it known that I, LEVI D. VAN VALKENBURGH, of Holyoke, in the county of Hampden, State of Massachusetts, have invented a certain new and useful improvement in Spindles and Bearings, of which the following is a description sufficiently full, clear, and exact to enable any person skilled in the art or science to which said invention appertains to make and use the same, reference being had to the accompanying drawings, forming a part of this specification, in which—

Figure 1 is a side elevation of my improved spindle, including the bearings therefor; Fig. 2, a vertical longitudinal section of the same; and Fig. 3 a side elevation of the bushing and its packing detached, the packing being shown in section.

Like letters of reference indicate corresponding parts in the different figures of the drawings.

My invention relates more especially to that class of spindles which are employed on single rail-spinning frames, twisters, &c.; and it consists in a novel construction and arrangement of the parts, as hereinafter more fully set forth and claimed, by which a more desirable and effective article of this character is produced than is now in ordinary use.

The nature and operation of the improvement will be readily understood by all conversant with such matters from the following explanation.

In the drawings, A represents the body or stand, B the spindle proper, and C the step. The spindle is provided with a sleeve-whirl, D, which is chambered, as shown at x, to pass over the upper portion of the body A, the sleeve-whirl D being provided at its lower end with a pulley or whirl, E, for the driving-belt. The sleeve-whirl is firmly attached to the spindle and is beveled or inclined as shown at m to "center" the bobbin and prevent it from vibrating. An elongated tubular bushing, G, provided with a threaded boss, f, at either end, is screwed into the upper end of the body A, which is interiorly threaded to receive it, and disposed around the bushing between it and the interior walls of said body. There is a packing, consisting preferably of a piece of ordinary tubular wicking, H, extend-

ing from near the lower to the upper boss, or so as to nearly cover the central portion of the bushing. The body A is enlarged near its center or provided with a thick annular flange, J, which rests on the rail of the frame when the spindle is in position for use. It is also exteriorly threaded and provided with the nut R for securing it in position on the rail. The flange J has a chamber or reservoir on its upper side, as shown at z, for receiving and holding the oil, the chamber being provided with a cover, i, having a suitable induction-orifice, q, through which the oil may be poured. There is a duct or conduit, r, extending from the bottom of the chamber z through the upper portion of the body A, to permit the oil to pass from the chamber to the wicking H, and also two ducts or conduits, a a, extending through the upper portion of the body of the bushing G, to permit the oil to pass from the wicking to the spindle B. An interiorly-threaded holder or thimble, K, is screwed onto the lower end of the body A, which may be secured in any desired position by the check nut L. The step C, which is adapted to receive the lower end of the spindle B, is secured in a vertical position within said holder and is provided with a lateral duct or conduit, l, through which oil may pass to the spindle from the reservoir r, the reservoir being filled through the duct n. A bent guard, M, is inserted in the flange J, and extends over the lower portion of whirl E, to prevent the spindle from being accidentally thrown or withdrawn from its step. This guard may be readily turned to one side when it is necessary to remove the spindle. A slot, h, is cut in the upper end of the bushing G for receiving a screw-driver or other suitable implement for turning the bushing as it is screwed into or withdrawn from the upper portion of the body. I form a groove or air-passage, d, in the upper boss, f, for admitting air to the chamber or space around the bushing in which the wicking is disposed, and thereby facilitating the absorption of oil; but this may be omitted, if desired.

I do not confine myself to the use of wicking for covering the bushing, as any suitable absorbent or conductor of oil may be employed which is adapted to perform the same

functions; neither do I confine myself to using but one duct, *v*, leading from the chamber *z*, or two ducts, *a*, in the bushing *G*, as these numbers may be varied as found necessary or 5 desired; nor to using the spindle with single rail-spinning frames. In spindles of this character much difficulty is experienced in properly lubricating the upper bearings or that portion which is near the top of the body *A*. 10 Difficulty is also experienced in adjusting the spindle vertically in such a manner as to cause the bobbin to be filled or "built" properly. My invention is designed to overcome these and other objections and difficulties, and to 15 that end I make use of the means described, whereby the spindle is perfectly lubricated and may be readily adjusted at any required height. The reservoir *r* is auxiliary to that in the flange *z*, and will not ordinarily be required, as sufficient oil usually finds its way 20 through the ducts *v a* and down the body of the spindle to lubricate the step *C*, without the necessity of filling the lower reservoir; but in case it does not, the step may be oiled 25 through the hole *n*. The check-nut *L* and hole *n* may be dispensed with, if desired, as the holder *K*, when screwed tightly onto the lower end of the body, will remain in position, and the reservoir *r* may be filled before the 30 holder is attached.

It will be obvious that the wicking and bushing afford a very simple and effective means of lubricating the upper bearing of the spindle; also that the adjustable holder will 35 enable the spindle to be adjusted vertically in any desired position.

Having thus explained my invention, what I claim is—

1. The combination of the holder *K*, provided with the chamber *r* and hole or duct *n*, the 40 step *C*, having the duct *l*, the body *A*, provided with the nut *L*, and the spindle *B*, substantially as described.

2. The combination of the body *A*, provided with reservoir *r* and with duct *v*, nuts *L R*, 45 spindle *B*, provided with whirl *E*, the bushing *G*, provided with bosses *f*, with the duct *a*, and with the groove *d*, the wicking *H*, the step *C*, provided with the duct *l*, and the holder *K*, provided with the reservoir *r* and 50 hole *n*, substantially as described.

3. The combination of the following instrumentalities—to wit, a spindle, a body in which the spindle is supported; an adjustable holder carrying a step for the spindle and disposed at the lower end of said body, a reservoir for oil disposed near the center of said body, a bushing for the spindle disposed in the upper portion of said body, a wick or absorbent for conveying oil from said reservoir 60 to the upper portion of said bushing, a duct for the oil leading from said reservoir to the wicking, a duct for the oil leading from the wicking through the bushing to the spindle, a whirl or pulley for the spindle, and a nut or 65 means for securing the body to the rail of a spinning-frame, substantially as described.

LEVI D. VAN VALKENBURGH.
